UNITED STATES PATENT OFFICE

CHARLES ROGERS AND CLARENCE ROGERS, OF CICERO, ILLINOIS, ASSIGNEES TO CROWN STOVE WORKS, OF CICERO, ILLINOIS, A CORPORATION OF ILLINOIS

DESIGN FOR A COMBINATION HEATER AND RANGE

Application filed February 21, 1931. Serial No. 38,785. Term of patent 14 years.

To all whom it may concern:

Be it known that we, CHARLES ROGERS and CLARENCE ROGERS, citizens of the United States, residing at Cicero, in the county of Cook and State of Illinois, have invented a new, original, and ornamental Design for Combination Heater and Range, of which the following is a specification, reference being had to the accompanying drawing, forming part thereof:

The figure is a perspective view of a combination heater and range, showing our new design.

We claim:

The ornamental design for a combination heater and range, as shown.

CHARLES ROGERS.
CLARENCE ROGERS.
